[57] CLAIM

The ornamental design for an infant toothbrush and teething object unit, as shown and described.

DESCRIPTION

FIG. 1 is a perspective view, showing my new design for an infant toothbrush and teething object unit;

FIG. 2 is a top plan view of FIG. 1, with the bottom plan and the right and left sides being identical to FIG. 2;

FIG. 3 is a front elevational view of FIG. 1;

FIG. 4 is a rear elevational view of FIG. 1;

FIG. 5 is a perspective view of a second embodiment of the toothbrush and teething object unit;

FIG. 6 is a top plan view of FIG. 5, with the bottom plan and the right and left sides being identical to FIG. 6;

FIG. 7 is a rear elevational view of FIG. 5; and,

FIG. 8 is a front elevational view of FIG. 5.
